DESIGN.

J. F. BRAYER & E. J. KING.
RANGE BACK AND SHELF.

No. 20,482.

Patented Jan. 13, 1891.

UNITED STATES PATENT OFFICE.

JOHN F. BRAYER AND EDWARD J. KING, OF ROCHESTER, NEW YORK, ASSIGNORS TO THE CO-OPERATIVE FOUNDRY COMPANY, OF SAME PLACE.

DESIGN FOR RANGE BACK AND SHELF.

SPECIFICATION forming part of Design No. 20,482, dated January 13, 1891.

Application filed June 25, 1890. Serial No. 356,729. Term of patent 7 years.

To all whom it may concern:

Be it known that we, JOHN F. BRAYER and EDWARD J. KING, of Rochester, New York, have invented and produced a certain new 5 and useful Design for Range Back and Shelf, of which the following is a specification, reference being had to the accompanying photograph, forming a part thereof.

- The central portion A of the range-back, 10 forming the flue, is rounded at the front, spreads slightly at the top, and is ornamented with a medallion K in relief, consisting of a series of conventionalized overlapping leaves a, springing from a central ring b and apparently secured by a ring c, passing through them, the ends of the ring being continued around, forming volutes passing through ring b. Within the ring b is a smaller ring d and a transversely-extending rib e, with a 15 spreading upper end, and over this and beneath the leaves extend two parallel ribs f, terminating in foliated finials g. Beneath the medallion K is an ornament E in relief, consisting of a series of conventionalized 20 leaves springing from parent stems arranged on each side, said stems starting from the rosette and intertwining, as shown. At the sides of the central portion A are the wings B, a vertical chain-like border C in relief extending between them. The contour of the wings B is substantially straight or slightly indented from the top to point h, and from this point to point i is in reverse-curved form, slightly retreating toward part A, and ornamented on the front with a double volute, the 25 upper part being formed by a rosette k, while the lower part is formed into a conventionalized folded leaf and a scroll m. From the lower portion of this leaf side B extends outward and then downward, the part below the recess being ornamented in relief with a reversed scroll n, having a rosette in the lower

part and an ornamental figure O resembling a conventionalized leaf, which, with the lower portion of the scroll, form the outline. Horizontal ribs p q are formed on the lower portions of the wings, and between them are located ornaments r in relief. The two wings are ornamented in the same manner, and the description therefor applies to both. At the 45 top of central portion A is arranged a horizontal shelf F, and at the rear of this an ornamental rail or top G, formed of two stems or rods H, with their inner ends arranged together and curved over a short horizontal bar 50 w, thence extended down to the shelf-top and gradually inclined upward, thence extended horizontally toward the sides, where they are curved around toward the shelf again and form parent stems, from which a series of 55 volutes or sprays spring, the whole forming grills or gratings, substantially as shown. The bar w is arranged slightly below the sides of the top and connects the two inclined portions of the stems. 65

What we claim is—

1. In the herein-described design for a range-back, the horizontally-extending shelf F and the vertical top rail composed of the side portions or stems H and the central depressed 70 portion, substantially as shown.

2. In the herein-described design for a range-back, the central column A, having the wings B indented and ornamented, and the rosette K and ornament E beneath it, all substantially as shown. 75

3. The design for a range back and shelf, substantially as herein shown and described.

JOHN F. BRAYER.
EDWARD J. KING.
